UNITED STATES PATENT OFFICE.

FRANCIS H. CRAFTS, OF BUFFALO, NEW YORK, ASSIGNOR TO THE E. & B. HOLMES WOOD WORKING MACHINERY DEPARTMENT, OF SAME PLACE.

DEVICE FOR ADJUSTING THE PRESSURE-PLATES OF PLANING-MACHINES.

SPECIFICATION forming part of Letters Patent No. 440,018, dated November 4, 1890.

Application filed February 12, 1890. Serial No. 340,191. (No model.)

To all whom it may concern:

Be it known that I, FRANCIS H. CRAFTS, a citizen of the United States, residing at Buffalo, in the county of Erie and State of New York, have invented certain new and useful Improvements in Devices for Adjusting the Pressure-Plates of Planing-Machines, of which the following is a specification.

The object of my invention is to produce an improved means for adjusting the pressure-plate of wood-planing or other machines, whereby any adjustment of the pressure-plate is rendered secure, so that it cannot be disturbed in any way by the action of the machine, all of which will be fully and clearly hereinafter described and claimed, reference being had to the accompanying drawings, in which—

Figure 1 is a side elevation, a portion being broken away so as to show the construction of the several parts. Fig. 2 is an under side view of one of the adjusting hand-wheels. Fig. 3 is a vertical cross-section through the center of the pressure-plate in or about line a b, Fig. 1, all portions beyond the section being omitted. Fig. 4 is a top view of one of the hand adjusting-wheels. Fig. 5 is an under side view of the pressure-plate and its adjusting mechanism.

In said drawings, 1 represents the well-known pressure-plate of a planing-machine. It is usually cast in one piece with the slotted cross-bar 2, the two ends 3 of which are secured so as to be movable up or down in the vertical slideways 4 in the holding-pieces 5. These two holding-pieces 5 are secured to the machine by bolts 6. Through a hole in the top of each of the holding-pieces is passed a vertical screw-threaded bolt 7, having a collar 8 rigidly secured thereto, so as to limit its movement upward in its holding-piece 5, and at the top of each bolt 7 is rigidly secured a hand-wheel 9. The under side of each hand-

wheel 9 is provided with a series of small teeth 10, and in each holding-piece 5 is a hole 45 11, in which is loosely fitted a steel pin 12, resting on a spiral spring 13. This pin 12 is beveled each way at the top, so as to form a wedge-shaped end 14, adapted to engage with the teeth 10. From this construction it will 50 be seen that the hand-wheel 9 may be turned by the hand in either direction, the springs 13 allowing the bolts or pins 12 to alternately move up and down as the teeth 10 move over the wedge-shaped edge of the same and thereby 55 raise or lower the pressure-plate. It will be further seen that when an adjustment is made the edges or points of the steel pins 12, being forced up by the spring 13 between the teeth 10, will rigidly hold the ratchet hand-wheels in position, so as to prevent them from 60 being disturbed or moved by the operation or jar of the machine, and thereby keep a perfect adjustment of the pressure-plate, as hereinbefore mentioned. The small teeth 10 may 65 be put on the periphery of the ratchet hand-wheels 9 and the pins or bolts 12 may be arranged in horizontal slideways; but the pins 12 would be in the way of the hands while 70 operating the wheels 9. Consequently its operation would not answer the purpose as well as that above mentioned.

I claim as my invention—

The pressure-plate of a planing or other machine fitted in vertical slideways, in combination with the screw-bolts 7, ratchet hand-wheels 9, provided with teeth on their under sides, vertical pins 12, and springs 13 for keeping them up in engagement with the teeth in the hand-wheels, substantially as and for the 80 purposes described.

F. H. CRAFTS.
